[57] CLAIM

The ornamental design for the side chair, as shown and described.

DESCRIPTION

FIG. 1 is a side elevational view of a side chair showing my design, the opposite side being a mirror image thereof.

FIG. 2 is a front elevational view;

FIG. 3 is a rear elevational view;

FIG. 4 is a top plan view; and

FIG. 5 is a bottom plan view thereof.

*FIG. 1**FIG. 2*

FIG. 3
